LUCIEN H. HANDY, OF OAKLAND, CALIFORNIA.

FLUSHING APPARATUS.

1,292,313.

Specification of Letters Patent. Patented Jan. 21, 1919.

Application filed January 2, 1918. Serial No. 209,846.

To all whom it may concern:

Be it known that I, LUCIEN H. HANDY, a citizen of the United States, residing at Oakland, in the county of Alameda and State 5 of California, have invented certain new and useful Improvements in Flushing Apparatus, of which the following is a specification.

My invention relates to the class of toilet 10 flushing-apparatus of that type which comprises a valve mechanism with a balancing fluid chamber upon the relief of the pressure in which the outlet valve opens for the flushing operation and gradually closes 15 again, thereby determining the period of flush which is ended by the restoration of the fluid pressure in the balancing chamber.

My invention has for its principal object 20 the installation of a flushing apparatus of this type, in connection with relatively small water service pipes, such as are commonly found in all buildings, thereby avoiding the provision of specially prepared pipes of sufficient diameter to insure the volume of 25 water necessary for flushing. Other objects and advantages of the apparatus will hereinafter fully appear.

My invention consists in the novel flushing-apparatus which I shall herein describe 30 in connection with the accompanying drawing in which the figure is a sectional elevation of the apparatus.

1 is a shell, which at one side near its lower portion has an inlet 2, and at its bottom, an 35 outlet 3. In the wall opposite that in which the inlet lies is a by-pass 4, the lower end of which communicates with the outlet 3, while its upper end registers with a passage 5 in a head 6, fitted to the top of the shell 1, and 40 held in registering relation by a dowel pin 7. A cap 8 screwed to the upper end of the shell covers the head 6. In the lower portion of the shell 1 is formed a seat 9 for the main-valve 10, which controls the outlet 3 and 45 normally cuts off said outlet from communication with the inlet 2. The main valve 10 has a stem 11 which is connected with the valve by a swivel joint at 12, and said stem carries a piston 13 fitted within the bore of 50 the shell 1, above the inlet 2. The swivel

connection at 12 permits the free movement of the piston 13 without tendency to bind or stick.

To the top of the piston 13 is fitted an adjustable screw stop 14, the function of which 55 is as usual to define the length of stroke of the piston, which by the displacement of the water above the piston, determines the period of flush.

In the head 6 is formed a port 15 with 60 which the passage 5 of the head communicates. This port opens into the shell 1 and is controlled from below by a pressure relief valve 16 the stem 17 of which passes upwardly through a packing gland 18, and terminates in a push button head 19 exposed for operation in the top of the cap 8. This push button indicates one of the usual forms of connections for operating the valve 16, though it will be understood that any usual 70 or suitable connection may be employed.

The lower extremity 17' of the relief valve-stem 17 forms a stop opposing the adjustable stop 14 of the piston 13, and is adapted to receive the contact of the latter 75 when the piston rises, and thereby to limit the stroke of the piston and define the flushing period. To effect a quick return of the relief valve 16 to close its port 15, there is provided a spring 20 under the push button 80 head 19.

Transversely through the wall of the upper portion of the shell 1, above the outlet 2, is made a constricted fluid pressure port 21, the size of which is predetermined by 85 the requirement of filling the shell with fluid, between the piston 13 and the pressure relief valve 16.

22 is a member of the apparatus which from its function may be termed a flushing 90 tank. It is, however, an enlarged part of the pipe system, of sufficient capacity, and is a closed vessel of the system. It receives in its bottom a nipple 23 which through a connection 24, communicates with the pipe 25 95 of the main water-supply. This pipe is fitted with controlling cock 26. One of the arms of the connection 24 is plugged at 27, and with another arm is fitted, by means of a packing connection 28, a tube 29, the other 100

end of sid tube communicating through a packing connection 30 with the constricted fluid pressure port 21 of the shell 1.

The flushing tank, vessel or compartment 22 also receives in its bottom, a nipple 31 which by an elbow 32 connects with a pipe 33, the other end of which is fitted to the inlet 2 of the shell 1.

In practice and to fully carry out the intent of the apparatus the main water-supply pipe is relatively small, say a $\frac{3}{8}$ pipe, such as is commonly found in the water systems of buildings, so that such pipes may be utilized, thereby avoiding the necessity of special supply pipes of greater capacity. But the flushing pipe 33 of the apparatus is a larger pipe of such capacity as may be determined upon, say $1\frac{1}{4}$ inch, for its proper function.

In the communication of the tube 29 with the connection 24 is interposed a safety screen 34 of a mesh smaller than that of the constricted port 21, say for example, if said port be a hole of $\frac{1}{16}$ inch diameter, the screen may be 100 mesh. This insures the non-stopping up of the port by foreign particles; and in case the screen needs cleaning, the removal of the plug 27 of the connection 24 will afford access of the finger or a small brush to reach the screen surface, but it will be noted that the screen is so placed with relation to the flow of water to the flushing tank 22 that it will be automatically cleansed. The outlet 3 of the shell 1 is to be suitably connected with the toilet bowl to be flushed.

The operation of the apparatus is as follows:

In normal condition, water from the main supply pipe 25, entering the closed tank-member or compartment 22, compresses a body of air therein, and the water also fills the flushing pipe 33 and its pressure is imposed upon the outlet valve 10 to hold it closed and also is imposed upon the under side of the piston 13, but without lifting the latter, for the pressure from supply pipe 25 is at the same time imposed through the constricted port 21 on top of said piston, and said pressure also holds the relief valve 16 closed.

Now by pressing in the push button 19 to cause the relief valve 16 to open its port 15, the balancing pressure above the piston 13 is relieved through said port and the passage 5 in the head 6 and the by-pass 4 in the wall of the shell, so that the pressure from the tank member 22, through the flushing pipe 33 lifts the piston 13 and the main valve 10 to open the outlet 3, whereupon the flushing volume of water from the tank 22 and pipe 33 passes through the outlet to the toilet bowl.

The relief valve 16 having been closed by the spring 20, and the space between said valve and the lifted piston 13 having been

deprived of a portion of its contents, the pressure from the inflowing water from the supply pipe 25 through the tube 29 and the constricted port 21 gradually forces the piston 13 down again and closes the main valve 10, thereby stopping the flushing flow and restoring the normal condition, the water from the supply pipe meanwhile again entering the flushing tank 22 and compressing the air therein.

By closing the cock 26 in the main water-supply pipe 25, and pushing in on the button 19, the whole system may be drained of water; and again filled with air to supply any loss thereof, whereupon the cock 26 may be opened again and the system restored to operative condition.

In addition to the advantage of installing this system in connection with relatively small supply pipes thereby avoiding the necessity of special large pipe, the following benefits may be noted. The wholly closed system tends to noiselessness. The closed tank member is sanitary in that no body of water is exposed to collect foreign matter, or for children to reach and play in. It is automatic in action, without the use of floats. There can be no overflow if the valve mechanism be open, because the volume of water from the supply pipe 25 is not sufficient, under these circumstances, to fill the larger flushing pipe 33.

I claim:

1. A flushing apparatus comprising a shell having an inlet, an outlet, and a by-pass leading from the shell interior to said outlet; a main-valve within the shell controlling said outlet; a piston connected with and operating said main valve and exposed below to the fluid pressure from the inlet; a relief-valve controlling the communication of the by-pass with the shell interior; means for opening said relief-valve to relieve pressure through the by-pass and thereby permit the main valve to open the outlet under the fluid pressure from the inlet and to establish the communication of the inlet with the outlet; a closed flushing tank incorporated in the fluid supply connections; a main-supply pipe leading to said tank; a pipe communicating with said main supply-pipe at a point prior to its connection with the tank and also communicating with the shell interior through a constricted port, at a point between the main valve piston and the relief-valve; and a flushing pipe leading from the tank to the inlet of the shell.

2. In a flushing apparatus and in combination with a controlling-valve mechanism of the balanced relief-pressure type substantially as described; a main supply pipe communicating through a constricted port with the balanced relief-pressure chamber of the valve mechanism; a flushing

pipe communicating with the main supply pipe and with the outlet of said valve-mechanism; and a closed flushing chamber incorporated in the communication between the 5 main supply pipe and the flushing pipe at a point beyond the communication of the supply-pipe with the valve mechanism.

In testimony whereof I have signed my name to this specification in the presence of two subscribing witnesses.
